(57) **CLAIM**

I claim the ornamental design for a tire, as shown and described.

DESCRIPTION

FIG. 1 is a front side perspective view of the tire;
FIG. 2 is a front view of FIG. 1;
FIG. 3 shows a left side view of FIG. 1;
FIG. 4 shows a right side view of FIG. 1; and,
FIG. 5 shows an enlarged section of the Tread of FIG. 1. The lines defining a box surrounding the section forms no part of the design.

Any surfaces of the design not shown, including interior surfaces and any surfaces shown in broken lines, form no part of the claimed invention.

1 Claim, 5 Drawing Sheets

FIG. 1

FIG. 2

FIG. 3

FIG. 4

FIG. 5
